UNITED STATES PATENT OFFICE.

ROY C. STEWART, OF PORTLAND, OREGON.

SPOON AND SPINNER BOOK.

1,339,231.

Specification of Letters Patent.

Patented May 4, 1920.

Application filed February 9, 1920. Serial No. 357,427.

To all whom it may concern:

Be it known that I, Roy C. STEWART, a citizen of the United States, residing at Portland, in the county of Multnomah and State of Oregon, have invented a new and useful Spoon and Spinner Book, of which the following is a specification.

My invention relates to spoon and spinner books, or, in other words, to pocket cases in which fish-hooks of the type known as spoons and spinners can be orderly stored and safely carried, and consists of two shallow metal trays hingedly connected with each other, having means to attach the eyes of the fish-hooks to the upper and lower edges of the trays, and having a lining of cork, or other suitable material, to engage the points of the fish-hooks.

The objects of my invention are to provide a neat and simple receptacle in which an angler may carry an assortment of fish-hooks in his pocket without fear of injuring himself or his hooks, or without having to extricate the desired hook from a tangled mass of barbed points, as is usually the case when the hooks are thrown promiscuously into an envelop or a bag.

I attain these objects with the mechanism illustrated in the accompanying drawing, in which—

Figure I is a plan view of my hook in open position;

Fig. II is a cross section through Fig. I along line 2—2;

Fig. III is a perspective view of my book in closed position.

Similar numerals refer to similar parts throughout the several views.

The two leaves of my book are stamped of metal in the shape of rectangular, shallow trays 1, and are hinged together at 2. The bottoms of the trays are, in this instance, lined with a layer of cork 3, although any other material which is capable of retaining the point of a fish-hook may be employed.

The supporting hooks 4, which are shown near the upper and lower edges of the trays, serve as convenient means of attaching quickly one of the links which usually form a part of spoons and spinners. However, to keep the links taut and to prevent an accidental dislocation of the fish-hook points from the lining 3, the supporting hooks 4 are fitted slidably within a metal strip 5 and equipped with small helical springs 6. The

shape of the metal strip, as clearly shown in Fig. II, resembles a Z-bar, with the lower leg riveted to the tray 1, the upper leg furnishing a protective covering for the springs 6, and the web providing the guide for the supporting hooks 4 and simultaneously a bearing for the springs 6.

A glance at the lower right hand edge of Fig. I, where the protective leg of the Z-bar has been broken away, reveals that each pair of supporting hooks 4 is bent of one single piece of wire. The advantages gained thereby are partly, that the middle section 7 furnishes the necessary counter bearing for the spring 6, and partly that the supporting hooks are prevented from turning, in other words, their points are always maintained in an upright position, ready to receive the fish-hook.

The supporting hooks of the upper edge are preferably placed in staggered relation to those of the lower edge, as are also those in one tray as against the other, this enables the economical utilization of all available space, without crowding one fish-hook on top of the other.

Any suitable lock 8 may be used to keep the casing closed.

This book is mainly intended for spoons and spinners and therefore need not be very long, however, by increasing the length proportionately, the same construction may advantageously be used for carrying those fish-hooks commonly known as fly-hooks.

Having thus described my invention, it will be seen that my objects have been accomplished, and, though I have shown the preferred form of construction, I reserve to myself the right to make minor changes, providing I do not violate the spirit and principle of my invention.

I claim:

In a spoon and spinner book, the combination comprising two shallow metal trays, hinges for the trays, a plurality of paired supporting hooks within the trays, means of imparting resiliency to the supporting hooks, Z-shaped metal bars to hold the supporting hooks, and a lining of resilient material, adapted to receive and hold the point of a fish-hook.

Signed by me at Portland, Oregon, this 3rd day of February, 1920.

ROY C. STEWART.
